UNITED STATES PATENT OFFICE

2,654,958

WIRE BUNDLE SPLITTER

Gilbert Walter Weber, Cleveland, Ohio, assignor
to United States Steel Corporation, a corpora-
tion of New Jersey

Application November 2, 1950, Serial No. 193,663

4 Claims. (Cl. 33—169)

1

The present invention relates to an apparatus for dividing bundles of wire into multiple units and has for its primary object the provision of a device whereby a bundle of wire may be accurately and easily divided into a predetermined number of multiple units without the necessity of weighing each of the multiple units to be cut from the bundle.

In cold wire drawing, it has been found to be more economical to draw the largest size bundles of finished wire possible. If a 300 pound bundle of wire is required and the wire drawing machine is capable of drawing 600 pound bundles, it is more economical to draw the 600 pound bundle and then split the same rather than stop the wire drawing machine each time a 300 pound bundle of wire is produced and remove it therefrom.

Although it is not new to split drawn bundles of wire, prior to my invention the problem has existed of splitting a bundle of wire with a fair degree of accuracy and at the same time accomplish such a splitting operation in the shortest possible time without undue physical effort on the part of the operator. It is this problem which my invention solves, as will be clearly understood by reference to the drawings, which will now be described, and the appended claims, which point out the novel features of my invention.

In the drawings:

Figure 1 is a plan view;

Figure 2 is a side elevation; and

Figure 3 is a view taken on the line III—III of Figure 1.

Referring more particularly to the drawings, reference numeral 2 indicates a horizontal supporting platform having three angularly disposed slots 4 therein and three spaced holes 6 therethrough. A tubular section 8 is welded or otherwise attached to the bottom of platform 2 in communication with each of the spaced holes 6. A nut 13 is welded on the bottom of each of the tubular sections 8 for receiving an adjusting screw 12. If desired, the lower ends of the tubular sections may be internally threaded to receive the adjusting screw 12 in place of providing nuts 13 for that purpose. An upright rod 14, having one end inserted into one of the tubular sections 8 with its bottom resting on the adjusting screw 12, extends upwardly from the surface of the horizontal platform 2.

A pair of L-shaped members 16 is welded or otherwise fastened to the rod 14 at a point 18 approximately midway between its ends. Legs

2

20 of the members 16 extend from rod 14 diverging from each other in a plane parallel to the platform 2. Each of the other legs 22 extends downwardly to the platform 2 with its axis parallel to the axis of rod 14, and is fitted through a hole 6 into tubular section 8. The bottom ends of the legs 22 rest upon adjusting screws 12.

The apparatus of my invention may be affixed to the side of a wire drawing bench 24 adjacent the drawing block by means of angle brackets 26, cleats 28 and angle bar 30 or by any other suitable means so as to be conveniently located for receiving a bundle of drawn wire to be split.

In setting forth the operation of the invention, the procedure used in splitting a 400 pound bundle into two 200 pound bundles will be described. In operation, the full-size 400 pound bundle W, with its core facing up, is laid on a flat surface and allowed to settle. After the bundle has settled, the depth of the core is measured by inserting a ruler or tape therein. This measurement constitutes the actual vertical distance from the top of the bundle to the bottom portion supported by the flat surface. This distance is divided by two to obtain the depth of the core of the desired 200 pound bundle.

The full-size bundle W is then lowered in a horizontal position onto the platform 2 so that the rod 14 and L-shaped members 16 are positioned within the core of the bundle. With the bundle W now resting on platform 2, the operator joggles or shakes the bundle so as to make sure that the convolutions of wire making up the bundle are sufficiently loose within the bundle as to allow the bundle to collapse and attain a natural given height when at rest and not restrained by tie wires. The adjusting screws 12 are then adjusted so that the legs 20 of the members 16 are at a height above platform 2 equal to one-half of the depth of the core of the full-size bundle W which value has been determined as described above. In order to facilitate the splitting operation, it is desirable to incline platform 2 at approximately $\frac{3}{8}$ inch per foot from front to back, thus the top half of the full bundle will tend to slide forward over the horizontal legs 20 toward the rod 14 as soon as it has settled into position on the platform 2.

With the bundle disposed on platform 2, as described above, the operator simply pulls that portion A of the bundle which projects above the legs 20 forward over the upper surfaces of the legs 20 until the rear portion of the inner periphery of the portion A contacts the rod 14 as

shown in Figure 2. The portion A which is hanging on the rod 14 now has the tie wires applied thereto and is cut free from the remaining portion B of the bundle resting on the platform 2. The operator then removes the bundle portion A from the rod 14 and applies tie wires to bundle portion B through the slots 4.

While one embodiment of my invention has been shown and described, it will be apparent that other adaptations and modifications may be made without departing from the scope of the following claims.

I claim:

1. Apparatus for dividing bundles of wire comprising a platform adapted to receive a bundle of wire, said platform having three spaced apart holes therethrough, a tubular member fastened beneath said plate at each of said holes, an adjusting screw threaded into each of said tubular members, a vertical rod in one of said tubular members extending upwardly from said platform, a pair of L-shaped members attached to said rod at a point between said platform and the top of said rod, said L-shaped members extending normal to said rod and diverging from each other, one leg of each L-shaped member extending downwardly through said platform with its axis parallel to the axis of said rod, said downwardly extending leg extending into one of the tubular members with its bottom end bearing on the adjusting screw.

2. Apparatus for dividing a bundle of wire comprising a horizontal platform adapted to receive a bundle of wire, an off-center positioned

rod extending vertically upward from said platform, and at least one L-shaped member attached to said rod at a point intermediate the ends thereof, one leg of each L-shaped member extending in a horizontal plane normal to said rod on one side thereof and the other leg extending downwardly to said platform, the distance from said rod to the downwardly extending leg of each L-shaped member being less than the inside diameter of said wire bundle.

3. Apparatus for dividing a bundle of wire as defined in claim 2 including means for adjusting the height of said horizontal legs above said platform.

4. Apparatus for dividing bundles of wire comprising a platform adapted to receive a bundle of wire, a rod extending vertically upward from said platform, a pair of L-shaped members attached to said rod at a point between said platform and the top of said rod, said L-shaped members extending normal to said rod and diverging from each other, and one leg of each L-shaped member extending downwardly to said platform.

25 GILBERT WALTER WEBER.
